FLOW VALVE

Charles S. Crickmer and Roy A. Lamb, Dallas,
Tex., assignors to Merle Tool Company, Dallas,
Tex., a firm of Texas

Application July 7, 1938, Serial No. 217,959

5 Claims. (Cl. 103—232)

This invention relates to new and useful improvements in flow valves.

One object of the invention is to provide an improved valve for controlling the admission of a lifting fluid, such as gas or air, into a liquid column, whereby said column is aerated and the liquid raised or lifted to the surface; the valve being an improvement on the prior patent issued to Charles S. Crickmer, one of the inventors herein, No. 2,144,144, January 17, 1939.

An important object of the invention is to provide an improved flow valve which may be mounted within a well tubing which tubing acts as a conductor for the lifting fluid; said valve having means for controlling the admission of the lifting fluid from the tubing into the well liquid column in the well casing and also having means for evenly distributing the lifting fluid throughout the column, whereby more efficient lifting of the well liquid is had.

Another object of the invention is to provide an improved valve wherein the outlet for the lifting gas is amplified or increased, which prevents choking or restricting the flow of the gas at the outlet, whereby a back pressure at the outlet, which tends to interfere with efficient operation of the valve, is eliminated.

Still another object of the invention is to provide an improved flow valve which is adapted to be mounted within the bore of a well tubing and which is provided with a plurality of radial outlet ports, whereby the gas passing through the valve is evenly distributed throughout the well liquid column so as to aerate the same equally throughout its cross-sectional area; there being means for centering or axially aligning the valve within the well casing to maintain the gas outlet ports of the valve spaced from the wall of the well casing so as to assure an equal distribution of said gas as it is admitted to the liquid column.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a transverse, vertical, sectional view showing a flow valve, constructed in accordance with the invention, mounted within a tubing string,

Figure 2 is a horizontal, cross-sectional view taken on the line 2—2 of Figure 1, and

Figure 3 is a partial isometric view showing the exterior construction of the valve housing.

In the drawing, the numeral 10 designates the usual well casing which has a well tubing 11 extending axially therethrough. A flow valve

assembly A is connected in the tubing string 11 and is arranged to control the admission of a lifting fluid, such as gas or air into the liquid column. It is the usual practice to mount a plurality of the flow valves at spaced intervals throughout the length of the tubing string, and since the valves are identical in construction, only one has been shown.

The flow valve assembly includes an elongate tubular housing or sleeve 12 which has its upper and lower ends externally screw-threaded, whereby said sleeve or housing may be connected in the tubing string 11 by means of suitable coupling collars 13. For centering or axially aligning the sleeve 12 within the well casing 10 the exterior of said sleeve or housing is formed with vertical ribs or guide wings 14 which are preferably formed integral with said housing. The ribs are spaced equally around the exterior of the housing and, as shown in the drawing, three of said wings are provided, although the number is subject to variation. The outer surface of each guide rib or wing is adapted to engage the bore of the well casing 10. The upper and lower ends of this outer surface of each wing are inclined, as shown at 14' so as to facilitate the lowering of the housing through the casing.

An elongate tubular cylinder 15 is mounted within the housing 12 and this cylinder includes an upper section B and a lower section C, which sections are suitably connected together by screw threads. The bore of the cylinder is closed at its upper end by a cap member 16, while its lower end has a plug 17 screwed thereto. The cylinder is disposed axially within the housing and is slightly longer in length than said housing, whereby its ends project into the tubing string. The bore of the cylinder 15 communicates with the interior of the well casing 10 through a plurality of radial nipples 18 which are preferably formed integral with the lower section C of the cylinder, being disposed near the upper end of said section. Three radial nipples 18 have been shown, but this number may be varied as desired, and each nipple is formed with a radial port 19. The outer surface of each nipple abuts the wall of the housing bore and a flanged screw 20 passes through an opening 21 in the housing 12 and has its inner end threaded into the bore 19 of each nipple. With this arrangement, the screws or plugs 20 serve to hold the cylinder 15 in position within the housing 12. Each plug 20 is formed with an axial bore 22 which registers with the port 19 of the nipple to which said plug is attached.

It is pointed out that the plugs 20 are preferably located between the guide wings or ribs 14 and a communication is thus established between the bore of the cylinder 15 which is located axially within the housing and the interior of

the well casing 10. It is pointed out that the combined cross-sectional area of the three ports 19 in the nipples 18 is equal to or greater than the cross-sectional area of the bore of the cylinder 15, whereby when fluid is flowing through the bore and outwardly through said ports, no restriction of such flow occurs as the fluid enters said ports. This eliminates the creation or building up of a back pressure within the bore of the cylinder 15 adjacent the inner ends of the ports 19.

10 The plug 17 is formed with an axial bore 23, which has its upper end communicating with the bore 15' of the cylinder 15. Radial ports 24 extend outwardly from the lower end of the bore 15 23 through the plug 17 and thus a communication 15 between the interior of the tubing string 11 and the interior of the well casing 10 is established through the ports 24, bore 23 of the plug 17, bore 15' of the cylinder 15 and then through 20 the ports 19 of the nipples 18.

For controlling the flow from the tubing to the casing, a tubular piston 25, having an axial bore 25', is movable vertically within the lower end 25 of the bore 15' of the cylinder, that is, within the lower section C. This piston is formed with a valve head 26 at its lower end and said head is adapted to engage an annular seat 27 formed at the upper end of the plug and surrounding the bore 23 thereof. A coiled spring 28 surrounds 30 the piston and normally holds said piston in a seated position, said spring being confined between the head 26 and an internal, annular shoulder 29 formed within the bore of the section C. A plurality of inclined ports 30 are provided 35 in the head 26 and communicate with the lower end of the bore 25'. When the piston is in its lowered position with the head engaging the seat 27, the openings 30 are not open to the flow through the bore 23 and thus a flow through the 40 cylinder is prevented.

When the piston 25 is raised, as will be explained, the valve head 26 is unseated and a flow from the tubing may pass through the inclined ports 30 and then upwardly through the bore 25' 45 of said piston. This flow then passes through the ports 19 of the nipples 18 and through the bores 22 of the plugs 20, whereby it enters the well casing. It is noted that the piston 25 acts 50 as a velocity tube and as the velocity of flow therethrough increases, the piston is moved upwardly under tension of the spring 28.

For metering the flow as the velocity through the piston 25 increases, a metering pin 31 extends 55 axially through the bore of the cylinder 15 above said piston. The metering pin is carried by a piston 32, solid in cross-section, which has its upper end exposed to the pressure within the well tubing through ports 33 formed in the section B. A coiled spring 34 surrounds the upper 60 end of the piston 32 and is confined between an internal shoulder 35, formed within the section B, and an external, annular flange 36 provided on the upper end of the piston. The spring normally holds the piston in the position shown in 65 Figure 1, which disposes the extreme lower end of the metering pin 31 adjacent the upper end of the bore 25' of the lower piston 25, when said lower piston is in its seated position.

70 In using the flow valves A in a well, plurality of the valves are connected in the tubing string 11 at various elevations therein. The well liquid which enters the lower end (not shown) of the well casing 10 rises to a predetermined level 75 therein, this level varying with the particular

conditions of the well. As the tubing string, having the valves A connected therein, is run into the well casing, a number of the valves will be submerged below the liquid level. At this time, the valves are in the position shown in Figure 1 with 5 the lower piston seated and the upper piston in a raised position. Gas, air, or other lifting fluid, is introduced into the tubing string 11, whereby the pressure thereof is built up within the tubing. The pressure of this gas or air acts through the 10 ports 24 in the plug 17 and also through the bore 23 of said plug against the lower end of the head 26 on the piston 25. The pressure of the well liquid within the well casing is of course acting through the ports 19 of the nipples 18 against 15 the upper end of the piston 25.

When the gas pressure in the well tubing reaches a predetermined point, which is sufficient to overcome the pressure of the liquid in the casing, plus the pressure of the spring 28 20 acting on the piston 25, the tubular piston 25 is moved upwardly so as to unseat the head 26. Unseating of the head permits the gas or other lifting fluid to flow upwardly through the ports 30 and then through the bore of the piston 25, 25 from where it flows through the ports 19 of the nipples 18 and into the well casing to aerate the liquid column. Since a plurality of the ports 19 are provided, it will be manifest that the gas or other lifting fluid escapes, or is ejected from the 30 bore of the cylinder in all directions, whereby said lifting fluid is equally distributed throughout the cross-sectional area of the well casing 10. This makes for an even distribution of the 35 gas or lifting fluid through the liquid column, whereby a substantially equal pressure throughout the cross-sectional area of the casing is obtained.

As the gas strikes the liquid column, the well 40 liquid begins to move upwardly through the well casing and as such movement commences, the load is lightened and the velocity of the gas or air entering the casing increases. The provision of a plurality of outlets into the well casing prevents a back pressure from being built up within 45 the bore of the cylinder around the metering pin 31 and therefore as soon as the liquid begins to move upwardly in the casing, an immediate increase in velocity of the gas flowing through the cylinder is had. Since the gas or other lifting 50 fluid is flowing through the bore 25' of the lower piston 25, the increase in velocity moves the piston upwardly under tension of the spring and, as it does so, the upper end of said piston moves upwardly with relation to the metering pin 31, 55 which pin is stationary at this time. Therefore, as the velocity of the gas admitted to the casing is increased, the volume of gas entering said casing is automatically reduced in accordance with such velocity.

The piston 25 continues its upward movement until an external shoulder 37 on said piston strikes the internal shoulder 29 within the bore of the lower section C at which time further upward movement of the piston is halted. In this 65 position, the upper end of the piston has moved with relation to the metering pin 31 so that the volume of gas or air entering the tubing is relatively small, although the velocity is comparatively high. When this velocity reaches a pre- 70 determined point, sufficient to reduce the pressure around the lower end of the piston 32, the pressure above said piston moves the same downwardly under tension of the spring 34. This 75 downward movement of the piston causes a seat

38, which is formed on the piston above the pin 31, to engage the upper end of the lower piston 25. When this occurs, further flow of the lifting fluid through the bore 25' of the lower piston 25 5 is prevented. The parts remain in this position until the well liquid in the casing rises sufficiently to build up the predetermined pressure necessary to move the pistons 25 and 32, after which additional lifting fluid is again introduced and the 10 operation repeated.

It is noted that the guide wings or ribs 14 on the exterior of the housing 12 serve to hold the valve assembly A centered or axially aligned within the bore of the well casing 10, whereby the ports 19 are at all times spaced from the wall of the well casing. If the ribs 14 were not employed, the housing 12 might move to one side of the well casing and dispose one of the outlets adjacent or contiguous to the wall of the casing. The gas 20 escaping through this outlet and flowing at a high velocity might injure the well casing and, in some cases, it has been found that it will form a hole in said casing. It is again noted that the cross-sectional area of the outlet ports 19 is at 25 least equal to the cross-sectional area of the cylinder bore, whereby no back pressure is present around the metering pin 31. The elimination of any back pressure at this point permits the upper piston 32 to move downwardly when 30 the predetermined pressure differential thereacross, as has been explained, is reached. By disposing the ports 19 around the housing 12 at equidistant points, an equal and even distribution 35 of the lifting fluid throughout the liquid column is obtained, which results in a more efficient lifting or raising of the liquid within the well casing.

The foregoing description of the invention is explanatory thereof and various changes in the 40 size, shape and materials, as well as in the details of the illustrated construction may be made, within the scope of the appended claims, without departing from the spirit of the invention.

What we claim and desire to secure by Letters 45 Patent is:

1. A well flowing device including, a well tubing, an elongate housing adapted to be connected in the tubing string and lowered therewith into a well casing, external guide members on 50 the housing for maintaining the housing in axial alignment with the casing, said housing having a plurality of radial openings therein, a tubular body of a smaller diameter than the housing mounted within the housing and having a passage 55 therein which has its lower end communicating with the interior of the well tubing, radial projections on the body adapted to abut the housing wall adjacent the openings in said housing and serving to align the body axially within the 60 housing, said projections having ports extending therethrough which lead from the passage and which register with the openings in the housing to form outlets establishing communication between the passage and the well casing, means 65 removably mounted in each opening and engaging in the port registering with said opening for securing the tubular body within the housing, and means movable within the passage and actuated by the differential in pressure between the lifting fluid in the tubing and the well liquid in the casing for controlling the flow through the passage.

2. A well flowing device including, a well tubing, an elongate housing adapted to be connected 70 in the tubing string and lowered therewith into

a well casing, external guide members on the housing for maintaining the housing in axial alignment with the casing, said housing having a plurality of radial openings therein, a tubular body of a smaller diameter than the housing 5 mounted within the housing and having a passage therein which has its lower end communicating with the interior of the well tubing, radial projections on the body adapted to abut the housing wall adjacent the openings in said housing 10 and serving to align the body axially within the housing, said projections having ports extending therethrough which lead from the passage and which register with the openings in the housing to form outlets establishing communication 15 between the passage and the well casing, the combined cross-sectional area of the outlets being substantially equal to the cross-sectional area of the passage whereby no restriction of flow from the passage through the outlets occurs, 20 means removably mounted in each opening and its registering port for securing the tubular body within the housing and means movable within the passage and actuated by the differential in 25 pressure between the lifting fluid in the tubing and the well liquid in the casing for controlling the flow through the passage.

3. A well flowing device including, a housing adapted to be mounted in a well tubing string and lowered therewith into a well casing, a tubular body mounted within the housing and having a passage which communicates with the interior of the tubing string, said body and housing having a plurality of radial outlet ports which establish communication between the passage and the well casing, radial guide wings extending longitudinally on the exterior of the housing and disposed alternately with relation to the outlet ports, said wings being of sufficient length to project above and below the outlets and being arranged 40 to engage the casing wall to hold said housing in axial alignment with the casing, whereby all of the outlets are spaced from the casing wall at all times to permit a flow therethrough, and means movable in the passage of the body and actuated by pressure differential thereacross for controlling the flow of fluid through said passage.

4. As a sub-combination in a well flowing device, an elongate tubular housing having a plurality of radial openings disposed therein, and a plurality of radially extending vertical guide wings mounted on the exterior of the housing and located between the openings, each guide wing being of such length that its extremities terminate in a plane above and below the radial openings, whereby each wing presents an uninterrupted surface in the horizontal plane of the openings.

5. A well flowing device including, an elongate housing having a plurality of radial outlet openings therein, radial guide wings on the exterior of the housing and disposed between the openings, a flow control means adapted to be mounted within the housing and having radial outlet ports 65 arranged to register with the openings in the housing, said flow control means controlling the admittance of a pressure fluid through the openings and ports into the housing, and means extending through each opening and removably 70 mounted in its registering port for removably supporting the flow control means within the housing.
